UNITED STATES PATENT OFFICE.

THEODORE HAUSER, OF CHICAGO, ILLINOIS, ASSIGNOR TO THE GARVY COMPANY, OF CHICAGO, ILLINOIS, A CORPORATION OF ILLINOIS.

LEAF-SUPPORT.

971,840.

Specification of Letters Patent. Patented Oct. 4, 1910.

Application filed February 2, 1910. Serial No. 542,680.

To all whom it may concern:

Be it known that I, THEODORE HAUSER, a citizen of the United States, residing at Chicago, in the county of Cook and State of Illinois, have invented a new and useful Improvement in Leaf-Supports, of which the following is a specification.

My invention relates particularly to leaf supports for couches, sofa-beds, etc. 10 My primary object is to provide a leaf support of exceedingly simple construction and capable of being cheaply manufactured and which operates in an improved manner.

The present invention, while relating to steel couches or sofa-beds of the type shown in my Patents Nos. 767059 and 789425 granted respectively August 9, 1904 and May 9, 1905, possesses important advantages over the structures disclosed in said patents 20 and also constitutes an improvement upon the structure set forth in my application No. 538,851 filed on the 19th day of January, 1910.

The invention is illustrated in its preferred embodiment in the accompanying drawings, in which—

Figure 1 is a broken transverse vertical sectional view of an all-metal couch equipped with my improvement, the full lines showing the swinging leaf of the couch in the horizontal position and the leaf-supporting link in the engaging or locking position; Fig. 2, a similar view showing the leaf raised somewhat above the horizontal position and the free end of the leaf-supporting link resting upon the longitudinal frame-member, which, in my improved construction, serves as a cam upon which the link may ride to effect a positive releasing operation; Fig. 3, a broken horizontal sectional view taken approximately as indicated at line 3 of Fig. 1; Fig. 4, a similar section illustrating the manner in which the leaf-supporting link is flexed to enable its free end to rise above the longitudinal frame-member mentioned when the leaf is swung above the horizontal position preparatory to effecting a release; Fig. 5, a section similar to Fig. 3, but with the parts in the position corresponding to Fig. 2; Fig. 6, a similar section showing the leaf dropped to the vertical depending position; Fig. 7, a broken sectional view taken as indicated at line 7 of Fig. 1; Fig. 8, a broken sectional view taken at line 8 of Fig. 2; and Fig. 9, a

broken inner view illustrating a slight modification, said view showing one of the corner uprights of the main frame, the guide-slot with which it is provided, and the longitudinal frame-member which serves as a cam. 60

In a couch or sofa-bed of the general construction herein shown, the main parts are a stationary frame A supporting a seat and one or more swinging leaves capable of assuming different positions. In the drawings 65 I have shown one swinging leaf B capable of assuming either a vertical depending position or a horizontal position, depending upon whether the structure is employed as a couch or a bed. The present invention relates to the means for supporting the leaf B in the horizontal position and for effecting automatic release thereof when it is desired to swing the leaf to the vertical depending position. 70

The stationary frame, in the illustration given, is of the usual form, generally speaking, and comprises end-standards A¹ (one only shown) and connecting angle-bars A² (one only shown). Each end-standard A¹ 80 comprises angle-form corner uprights 1 (one only shown) supported on a base 2, and an angle-form cross-member 3 joining the upper ends of the uprights 1. The top-member 3 has an end 4 which projects outwardly beyond the upright 1, and the end-member 5 of the leaf is connected with the extension 4 by a pivot 6. The upright 1 has a flange 7 which is turned toward the opposite side of the frame and a flange 8 which is turned toward the opposite end-standard of the frame. The flange 8 is provided above the longitudinal frame-member A² with a guide-slot 9 whose lower end affords a locking shoulder 10. The longitudinal frame-member 85 A² is shown connected with the upright 1 by the rivet 11; and braces 12 connect the upright 1 with the member A². The end of the member A² is located at the inner side of the flange 8 of the upright 1 and is shortened 90 so as to afford a space 13 between the extremity of said member A² and the flange 7 of said upright 1. 95

The end-member 5 of the leaf B has a flange 14 which is located in a vertical transverse plane and is connected by the pivot 6 to the down-turned flange of the top cross-member 3 of the main frame. A leaf-supporting link 15 has its outer end joined by a pivot 16 to the flange 14, and said link ex- 100 110

tends through the guide-slot 9 of the upright 1. Said link is provided at its lower edge near its free end with a notch 17 whose outer side affords a locking shoulder which 5 co-acts with the locking shoulder at the lower end of the slot 9. When the leaf B is in the horizontal position, the notch 17 engages the lower end of the slot 9, while the extremity of the link projects into the space 13 adjacent 10 the end of the longitudinal frame-member A². The free end-portion of the link 15 is designated 18 and may be regarded as a cam extension. It will be observed, by reference to Fig. 1, that when the link 15 is in the locking position, the lower corner of the extension 18 of the link projects slightly below 15 the inturned flange 19 of the longitudinal frame-member A².

The link 15 may comprise a substantially straight rolled steel bar which may be readily produced by a press operation, in which operation the notch 17 may be formed. The guide-slot 9 is somewhat wider than the thickness of the link, and is provided at or near 20 its upper end with an inclined surface 20 which normally overhangs the link 15 in the locking position thereof, said inclined surface preferably extending from the outer edge of the slot, that is, the edge nearest the flange 7, upwardly and inwardly toward the free edge of the flange 8, so that the upper end of the slot 9 is contracted to approximately the thickness of the bar or link 15.

As stated, when the leaf B occupies the horizontal position, the locking shoulder of the link engages the stationary locking shoulder of the frame, and the extension 18 of the link lies adjacent the end of the flange 19 of the longitudinal frame-member A². When it is desired to effect a release, the leaf B is swung upwardly to approximately the position indicated by dotted lines in Fig. 1, in which operation the upper edge of the link engages the inclined cam-surface 40 at the upper portion of the slot, and the link is flexed somewhat as indicated in Fig. 4 during the time that the extension 18 is passing the end edge of the flange 19. When the extension 18 rises above the flange 19, the link straightens, and the extension 18 slips or shifts laterally onto the upper surface of the end portion of the flange 19, whereupon the leaf B may be lowered (rapidly or slowly) to the depending position, the link-extension 18 riding upon the flange 19 as a cam in this movement, so that the locking notch 17 will be positively carried past the stationary locking-shoulder 10. After the locking notch has cleared the stationary locking-shoulder during the operation of dropping the leaf, the link resumes its normal position in a plane adjacent the end edge of the flange 19, as shown at Fig. 6, so that when the leaf is raised again to the horizontal position the leaf-supporting

link will enter the space 13 and the locking notch will be free to engage the stationary locking-shoulder. By reason of the disposition and connection of the parts, the tendency of the leaf-supporting link is to resume the position shown in Fig. 6 when the leaf is lowered. If desired, the corner of the flange 19 may be rounded or beveled slightly, as indicated at 21, so that as the leaf is lowered from the position shown in full lines in Fig. 2 the link-extension 18 will first ride upon the upper surface of the flange 19 until the locking notch has cleared the stationary locking-shoulder, and the link-extension will then engage the beveled surface 21, which will tend to throw the link positively laterally over into its normal plane parallel with the end of the couch-frame.

In Fig. 9 I have illustrated another expedient for insuring the return of the leaf-supporting link to the plane adjacent the outer edge of the guide-slot, so that the link-extension 18 will be sure to enter the space 13 when the leaf is again raised to the horizontal position. According to this modification, I bevel the bottom of the guide-slot 9 inwardly and upwardly, as indicated at 22, so that when the leaf is swung from the dotted position shown in Fig. 2 to the position shown in full lines in Fig. 1 the link, which rests upon the bottom of the guide-slot, will be sure to slip to a position adjacent the outer vertical wall of the guide-slot. This expedient is not at all a necessary feature, but may be employed if desired.

It will be noted that my improved construction provides for effecting an automatic release of a positive character, so that the leaf may be manipulated as slowly or as rapidly as may be desired, and the releasing operation will be certain in every instance. It will be understood, of course, that ordinarily the construction is duplicated at each end of the leaf. Moreover, it is noteworthy that the improved result is obtained without the necessity of employing any extraneous parts. That is to say, the result is obtained by suitably fashioning the guide-slot, shortening the longitudinal frame-member A² and properly disposing the parts with relation to each other. It follows that my construction provides for a material reduction in the cost of production, which in goods of this class is a very important consideration. Moreover, the width of the locking-notch of the link may be as great as desired, thus providing for complete certainty of the locking operation when the leaf is raised to the bed-forming position. In this respect, the device has marked advantages over the constructions in which momentum and inertia are depended upon to effect a release, since it is usually necessary in such constructions to

employ a narrow locking-notch, requiring careful manipulation in the locking operation.

The foregoing detailed description has been given for clearness of understanding only. Hence no undue limitation is to be understood therefrom, but the appended claims are to be construed as broadly as permissible in view of the prior art.

10. What I regard as new and desire to secure by Letters Patent, is—

1. In a structure of the character set forth, the combination of a main frame provided with a link-receiving guide having an inclined surface adapted to shift said link laterally, a leaf pivotally connected with said frame, a pivoted link having a locking shoulder, and a connecting frame member located beneath said guide and of a length less than the width of the main frame, whereby the inner end of the leaf-supporting link is caused to rest between the end of said connecting frame member and the main frame when the leaf is in the same horizontal plane with said main frame, and to ride upon and be raised by said connecting member when the leaf is raised to an abnormally elevated position and the free end of the link caused to be shifted laterally by the inclined surface of the guide, for the purpose set forth.

2. In a structure of the character set forth, the combination of a frame having an end-standard provided with an angle-form upright with a flange extending toward the opposite end-standard of the structure, said flange having a guide-slot with an inclined surface extending from the outer side wall of the slot, a longitudinal angle-bar frame-member extending from said flange with a space between it and the other flange of said upright, a leaf pivotally connected with said frame, and a leaf-supporting link pivotally joined to said leaf and provided at its lower edge with a locking-shoulder and adjacent thereto with an end-extension which normally projects into said space and lies adjacent the end-edge of said longitudinal angle-bar, whereby said extension will be shifted laterally toward the opposite end of the structure and onto said longitudinal frame-member when the leaf is swung to an abnormally high position, thereby to effect a positive release when the leaf is dropped.

3. In a structure of the character set forth, the combination of a main-frame comprising end-standards of angle-bar construction, said end-standards having angle-form uprights, longitudinal frame-members of angle-bar form connecting said uprights and having inturned flanges, spaces being left between the ends of said flanges and the flanges of said uprights which are parallel with the ends of the structure, a leaf pivotally connected with said main frame,

guide-slots in the flanges of said uprights, said guide-slots having inclined portions at the upper ends of their outer walls, and links pivotally connected with said leaf and extending through said guide-slots, said links having notches at their lower edges and end-extensions which normally lie in said spaces adjacent the ends of the inturned flange of said longitudinal frame-member when the leaf is in the locked position, whereby said end-extensions will be shifted laterally onto the longitudinal frame-member when the leaf is raised to an abnormally high position and will ride upon said frame-member to carry the locking-notches clear of the guide-slots when the leaf is lowered to the vertical depending position.

4. In a structure of the character set forth, the combination of a frame provided with a guide-slot having an inclined cam-surface at the upper portion of one side wall, a leaf pivotally connected with said frame, a link pivotally connected with said leaf and provided with a locking-notch and an end-extension, a cam carried by the frame and projecting inwardly from the side thereof and located normally adjacent one side of said end-extension when the leaf is locked in the horizontal position, whereby said end-extension will be shifted onto said last-named cam when the leaf is raised to an abnormally high position, and means for guiding the free end of the link, after the locking-shoulder has cleared the locking position in the descent of the leaf, to the plane which said link normally occupies in its locked position.

5. In a structure of the character set forth, the combination of an end-standard having a corner upright with an end flange and a side flange, said side flange provided with a guide-slot having at its upper portion an inclined surface extending away from the wall of the slot which is adjacent said end-flange, a leaf pivotally connected with said end-standard, a link pivotally connected with said leaf and provided with a locking-notch adapted to engage the lower end of the guide-slot and having an end-extension, and a longitudinal frame member connected with said upright and having an inturned flange with its end edge separated from the end flange of said upright by a space normally occupied by said link-end-extension when the leaf is locked in the horizontal position, said inturned flange having a beveled corner adapted to guide the free end of the link back to the plane which it normally occupies in the locking position.

6. In a structure of the character set forth, the combination of a frame provided with a guide-slot and a cam-surface at the upper portion thereof, a leaf pivotally connected with said frame, a link pivotally connected with said leaf and extending through said

guide-slot, said link having a locking-shoulder at its lower edge and an end-extension, and a cam within the frame adjacent said end-extension and in such relation thereto
5 that the link will be flexed when the leaf is swung above the normal locking position and said end-extension will spring over onto

said last-named cam and ride thereon in the operation of lowering the leaf.

THEODORE HAUSER.
